(57) **CLAIM**

The ornamental design for a set screw, as shown and described.

DESCRIPTION

FIG. 1 is a front perspective view of a first embodiment of a set screw in accordance with the present invention;

FIG. 2 is a side view of the set screw of FIG. 1;

FIG. 3 is a front view of the set screw of FIG. 1; and,

FIG. 4 is a rear view of the set screw of FIG. 1.

The broken lines shown in the Figures represent portions of the set screw that form no part of the claimed design.
